TABLET MACHINE

Charles J. Westin and Charles J. Beck, Philadelphia, Pa., assignors to F. J. Stokes Machine Company, Philadelphia, Pa., a corporation of Pennsylvania

Application March 7, 1934, Serial No. 714,409

3 Claims. (Cl. 107—17)

The present invention relates to rotary, tablet-compressing machines, and pertains particularly to new and useful improvements in the principles of construction which result in economy of manufacture, greater convenience and efficiency of operation, and which materially increase the production rate of the machine.

More specifically, this invention is particularly directed to means for yieldingly supporting the lower roll in operative position; means for adjusting the tension with which said roll is supported; and means for indicating the adjustment as it is made.

Another feature of our invention is means for ejecting the tablet by simultaneously lifting both the punches and the tablet between them, and then lifting the top punch away from the lower punch, and away from the tablet thereon.

Other objects relating to details and economies of construction and operation definitely appear from the description to follow.

In the drawings:

Fig. 1 is a perspective view, in elevation, of our device;

Fig. 2 is a cross-section through a tablet made on the machines of the prior art;

Fig. 3 is a side elevation, with parts in cross-section, of some details of the machine;

Fig. 4 is a diagram and development of parts of the machine and of their operation;

Fig. 5 is a top plan view of the lower cam in the adjacent parts; and

Fig. 6 is a side elevation of the lower cam.

In that embodiment of our invention chosen for illustration in the drawings, and particularly Fig. 1, this type of machine is shown as consisting of a frame 11 provided with a base 12, and a table 13 having a central spindle thereon, on which a rotating head 15 is mounted. The head 15 is mounted for rotation in the direction of the arrow "A", as, for example, by a worm-gear (not shown) attached to it and co-operating with a worm (not shown) on shaft 18, which may conveniently be driven from a prime mover through pulleys, or by any other convenient means. The head 15 is of such construction that a number of rings or annular disks are superimposed with smaller rings or necks in between forming a structure of several stories and of diameters to suit the co-acting mechanism. A plurality of apertures are spaced around the head and cut clear through the several stories to form bearings and seats for the plurality of upper punches 20, lower punches 21 and molds 22 (best seen in Fig. 3). The punches are caused to co-operate

with the mold 22 through cam tracks; 23 for the upper, 54 for the lower; or through the upper compressing roll 25 and lower roll 26.

The diagram Fig. 4 shows step-by-step in sequence the functions of each set of punches for a complete revolution of 360° of the head 15. The degrees marked along the top are arbitrarily chosen and merely serve the purpose of showing the synchronized action of the parts. At the 0° line the lower punch 21 starts down opening the mold cell and the powder flows in, completing the filling at about 95° where the punch again rises, lifting some of the powder out of the mold, the excess being scraped off at 140°. From this point the lower punch may travel straight or be lowered as the case may be, until it strikes the roller 26 at the same time, or approximately so, that the upper punch 20 strikes the roller 25 and the powder is compressed into a tablet at 270°. At the 330° line the tablet has been lifted out of the mold and rides off the mold table 30 onto the discharge chute 37 (Fig. 1) at about 350°.

Tablet-compressing machines are built in a number of sizes and are primarily classified according to the maximum pressure they can exert on the largest size tablet within the range of the machine, but the pressure must be adjustable so that it can be reduced when smaller size tablets are to be made. For example, a three-ton machine may have a range from $\frac{1}{8}$ inch diameter tablet up to $\frac{3}{8}$ inch diameter or tablets of areas from .012 square inch up to .306 square inch, and it is evident that the same pressure should not be used for the small as for the large. In our device, the upper roll 25 is usually rotatable on a fixed shaft 80. The lower roll 26 rotates on shaft 59, mounted in lever 57 which is supported on one end by fulcrum 58 fastened to table 13, and on the other end by pin 60 connecting it through the adjustable linkage 61 and pin 64 to the safety release lever 67. This safety release lever 67 has its fulcrum at 66 supported by clevis 65 which is attached to the base 11. At the far end 70 the lever 67 is attached to spring 76 which is fastened to the pad 79 of base 11 by eyebolt 78. Spring 76 is enclosed in a casing or spring-chamber 77 which serves a three-fold purpose: completely encloses the spring 76; supports end 70 of lever 67 at a predetermined level regardless of the tension exerted on 70 by spring 76; provides visible means for controlling the calibrating as well as the adjustment of the spring tension. Heretofore, with the old compound leverage and weight mechanism used as a yieldable support for the lower roller 26, it was very diffi-

cult to get the correct pressure when changing from one size tablet to another and usually meant a considerable amount of experimenting but with our invention, using the indicator 75 in combination with the graduated scale 74, the adjustments can quickly and easily be made. It is understood that we provide graduation on scale 74 to suit the tension produced at various points when the spring 76 is stretched in making the adjustments.

5 The indicator arrow 75 is mounted on a block 73 attached to eyebolt 68, which extends through lever-end 70 and is threaded to co-operate with handwheel 69 for the purpose of increasing or decreasing the pressure as the case may be.

10 15 It is a well known fact that springs gradually stretch and for that reason we have provided for recalibrations by mounting plate 74 adjustably on its support. By relieving spring 76 of all tension and setting the 0 graduation of scale 74 opposite the indicator arrow 72, the pressure-indicating device is re-calibrated.

15 20 We have also provided a safety device to prevent stressing the machine beyond its rated pressure. This consists in a series of spacers 71 made in varying thicknesses and placed between indicator blocks 73 and lever-end 70 to stop the adjustment of eye-bolt 68 when the maximum pressure is reached. After re-calibrating the indicator at the 0 graduation as described above, a check can be made for the maximum pressure by adjusting the indicator arrow 75 up as far as it will go and noting the difference between the arrow and the maximum graduation; removing sufficient spacers will restore the pressure range.

25 30 35 In the manufacture of compressed tablets from powdered or granular material, there often is, as shown in Fig. 2, a tendency for the upper portion 8 of the tablet to separate from the main portion 7. This is a serious difficulty known as "capping", and is caused either by unrelieved internal strains or by entrapped air and/or other causes. In many instances, it has been necessary to operate the old type of machines at half the production speed on account of this difficulty, but we have found that, through the use of our improved construction, the "capping" is eliminated, and the machines may be operated at their full-rated capacity.

40 45 50 As mentioned above, the "capping" is eliminated through the use of our invention, herein to be referred to as the double-function of the lower punch. Heretofore, these machines were constructed so that the upper punch 20 would be lifted out of mold 22 by cam 53 as soon as the punch-head would clear the roll 25, Figs. 3 and 4. Considerable power is required to break punch 20 loose and lift it out of the mold 22 after compressing a tablet, and it was, therefore, necessary to make use of all the available space to provide a gentle slope on the punch-lifting cam 53. The lower punch 21, however, would ride on, until it reached incline 55 of cam 54 at a farther distant point than the upper punch, before it would be forced by incline 55 to lift the tablet out of mold 22. By this method, the tablet was unsupported on top for a considerable distance before the ejection as well as during the ejection. However, we have found that allowing the upper punch 20 to remain tight and undisturbed on the tablet for a longer time interval is very beneficial in strengthening the tablet, because it gives any entrapped and compressed air a chance to escape, thus eliminat-

ing the tendency of "capping". We have also found that these conditions are further improved by making the lower punch 21 lift the upper punch 20 out of the mold 22 by means of the tablet. For this purpose, it is necessary to provide more space for cam 54 so that incline 55 could be made a more acute angle with the horizontal line, or, in other words, slope more gently from the surface of table 13, and thus gently ease the tablet and upper punch out of the mold, without decreasing the range of adjustment for the lower roller 26. One of the means resorted to, in providing the needed room, is to make the point of incline 55 at the top of table 13 the same thickness as the distance roll 26 extends above the table, when set for the thickest tablet, instead of a sharp point as heretofore. A bridge 56 also has to be provided to carry the punch from the roll to the cam when using this low position of the roll. As a result, an increase of 100 percent in the production has been obtained in many cases.

We do not intend to be limited save as the scope of the prior art and of the attached claims may require.

We claim:—

1. In a tablet machine, the combination of, a pair of rolls, a base, a lever pivotally mounted on said base and pivotally supporting one of said rolls thereon, a second lever pivoted on said base adjacent said first lever, a link connecting said levers together, a hand-wheel arranged to adjust the length of said link, a spring connected to said base, a spring chamber completely encircling said spring and underlying one end of said second lever so as to provide a stop for said second lever in one direction of movement thereof, an eye-bolt connected to said spring, and a hand-wheel having screw threaded engagement with said eye-bolt and bearing on said second lever so as to provide means for adjusting the tension with which said spring stresses said second lever.

2. In a tablet machine having a pair of rolls and a pair of vertically aligned punches and means for conveying said punches between said rolls and thereby moving them toward each other to compress a tablet between them, the combination of, a linkage pivotally supporting one of said rolls, a spring connected to said linkage to yieldingly retain said roll in operative position, means for contacting with the lower of said punches after they have passed through said rolls and for lifting said punches and the tablet between them simultaneously by pressure applied to the lower of said punches and with the upper of said punches solely supported on the tablet, and second means to the rear of said first-mentioned means in the direction of movement of punches and co-operating with the upper of said punches for then lifting the upper of said punches away from the lower of said punches and the tablet thereon. 45 50 55 60

3. In a tablet machine, the combination of, a pair of rolls, a pair of vertically aligned punches, a mold for receiving the operative ends of said punches therein, a table for conveying said punches and said mold between said rolls, a cam co-operating with the lower of said punches and having a face adjacent the lower of said rolls and sloping relatively gently in relation to the surface of said table to thereby simultaneously lift both said punches and a tablet between them by pressure applied to the lower of said punches 75 65

and with the upper of said punches solely supported on the tablet, and a second cam co-operating with the upper of said punches and having a face to the rear of said face of said first-mentioned cam in the direction of movement of said punches and sloping relatively sharply in relation to the face of said tablet to thereby lift

the upper of said punches away from the lower of said punches and the tablet thereon after said punches and said tablet have been partially lifted.
